UNITED STATES PATENT OFFICE.

STANLEY R. HARDWICK, OF TOLEDO, OHIO, ASSIGNOR OF ONE-HALF TO JAMES A. WOOD, OF TOLEDO, OHIO.

BURNER APPARATUS.

1,363,868.

Specification of Letters Patent. Patented Dec. 28, 1920.

Application filed June 23, 1919. Serial No. 306,250.

To all whom it may concern:

Be it known that I, STANLEY R. HARDWICK, a citizen of the United States of America, residing at Toledo, Lucas county, 5 Ohio, have invented new and useful Burner Apparatus, of which the following is a specification.

This invention relates to the control of fuels for combustion.

10 This invention has utility especially in fluid fuel burning installations.

Referring to the drawings:—

Figure 1 is a view, with parts broken away, of an embodiment of the invention in 15 an installation for heating purposes as for residences;

Fig. 2 is a detail view with parts broken away, of the air line control valve for the fuel;

20 Fig. 3 is a sectional view of the air line check valve;

Fig. 4 is a longitudinal section of the carburetor;

25 Fig. 5 is a plan view of the carburetor; Fig. 6 is a plan view of the heating coil in the furnace; and

Fig. 7 is a fragmentary section of the furnace showing the burner passage up through the furnace from the carburetor.

30 In the installation of the device of the invention herewith especially in connection with heating plants for buildings or residences, it is desirable to have the apparatus operate automatically. For instance a ther-

35 mostat 1 may control a thermostat motor 2 for throwing in or out, an electric motor 3 which electric motor 3 may drive a rotary air pump 4. This pump 4 may have a by pass line as shown to control flow of com-

40 pressed or power driven air in the air supply line 5 extending to tank or reservoir 6. This tank or reservoir 6 may have a liquid fuel as gasoline or kerosene oil therein, which is preferably maintained at a level above that

45 to be shown in sight glass 7. In the lower region of this oil reservoir 6 is a screen 8 in communication by line 9 past a minute vent opening 10 near the top of the reservoir 6 with the oil or liquid fuel supply line 11.

50 The flow of fuel in this line 11 may be adjusted by a valve 12 in addition to the adjustment by the pressure as varied by the bypass pipe at the pump 4 which has a regulating valve 13 therein. The working pres-

sure on the tank 6 may be disclosed by the 55 gage 14.

The air line 5 as a pressure air supply, besides extending to the tank or reservoir 6 has a portion 15 extending therebeyond, which portion 15 has a small branch line 16 60 extending to auxiliary reservoir or housing 17, containing cylinder 18, with piston 19 therein, (Fig. 2), normally pressed downward by a spring 20, which position of the spring 20 may be adjusted as to compression 65 by nut 21. The piston 19 has on its upper side a collar 22 fast with stem 23. Accordingly pressure air entering the cylinder 18 from the line 16 tends to push the piston 19 upwardly and compress the spring 70 20, thereby through the collar 22 lifting the stem 23 connected to rod 24 operating valve member 25 away from seat 26 in valve housing 27. This allows a gas supply from line 28 passing check valve 29 from the 75 main gas line 30 to flow through the line 31, valve 32 and line 33 into carburetor 34. The adjustment of the nut 21 may be such that the stem 23 may normally through the rod 24 hold the valve member 25 a sufficient 80 distance from the seat 26 to allow of such flow of gas from the line 28 through the valve 27 and into line 31 to provide a pilot or heating gas supply in the carburetor 85 chamber 34.

This carburetor chamber 34 has at its discharge end a nozzle 35 along the lower side of this cylindrical carburetor chamber 34. This carburetor is disposed in the ash door opening 36 of a furnace 37, and in that position is preferably inserted in a duct 38 extending inward and upward to the region of the grate or fire box of the furnace where fuel therefrom may be dispersed in a grid 39 of fire brick, as a general heating region 95 for the furnace (Fig. 7).

From the pressure air line 15, beyond the branch 16, extends pressure air line 40 to housing 41 which acts as a check valve, having therein a plunger 42 (Fig. 100 3) operable in a seat having fluted portions or grooves 43 of one length alternating with shorter fluted portions 44 therebetween. The purpose of this fluting of various lengths about the plunger 42 is that there 105 may not be chatter in the gradual unseating of the valve 42 from the action of pressure from the air line 40. This valve plunger

42 carries a stem 45 and is normally urged downward by a spring 46 acting from a guide piston 47, the position of which in the housing 41 is adjusted by a screw 48. This 5 means of adjustment of the spring 46 and accordingly adjustment of the opening of this check valve 42 for allowing the pressure air from the line 40 to pass through this check valve 42 into line 49 *en route* to 10 the furnace 37 by way of the ash door opening 36 and upward to coil portion 50 (Fig. 6) to be thoroughly heated, and as hot air, thence to pass by line 51 to adjacent the carbureter 34 where it may connect to the pressure oil line 52 and be delivered as a spray 15 by nozzle 53 into the carbureter.

Accordingly the device of this disclosure is readily adaptable for quiet operation to either a gas supply or a liquid fuel supply 20 and in either instance the hot air for the complete combustion is directly supplied to the carbureter 34. Preferably in operation there is some gas supply maintained or at least sufficient to start the operation of the 25 device but when once started it may be then continued by cutting the supply off by the valve 32 and opening the valve 12 control the amount of liquid fuel which it is desired to have passed to the carbureter 34. The air 30 pressure as controlled by the motor 3 from the thermostat will normally control the flow of gas if operating on gas by the position of the valve member 25 in the housing 27. If running on liquid fuel the control 35 may be by the amount of pressure on the tank 6.

When the region to be heated has its 40 temperature controlled by the thermostat 1 and when the temperature for which the apparatus is set is exceeded, the motor 3 is 45 shut off. The shutting off of the motor, if the burning of the fuel be gas, at once cuts off the gas by lowering the valve member 25 in housing 27. On account of the clearance for supplying the pilot in not fully closing 50 the valve 27, there is still gas flow to keep the carbureter 34 heated.

If the operation be on liquid fuel from the reservoir 6, when the motor 3 is cut off the 55 pressure on the line 5 at once drops and thus relieves the pressure in the chamber 6. The slight opening 10 in the line 9 precludes the siphoning of the fuel by line 11 so that at once there is a discontinuance of the flow 60 of the liquid to the carbureter 34. The advantage of the discharge opening 35 from the carbureter 34 is that in operation there may be no condensation or collection of liquid in this carbureter the heated air 65 supply under pressure from small jet 53 expelling everything from this heat insulated jacketed carbureter making it self-cleaning at all times. There is some clearance about the eye of the duct 38 adjacent to the discharge opening 35 so there is a supple-

mentary air supply in addition to the heated air supply from the coil 50.

What is claimed and is desired to secure by Letters Patent is:

1. A burner, a reservoir, a fuel supply 70 from the reservoir for the burner, a valve for the fuel supply, and an air supply to the reservoir for forcing fuel supply to the burner and having a line coacting to open the fuel supply valve simultaneously with the 75 air forcing of the fuel supply to the burner.

2. A burner, a reservoir, a fuel supply from the reservoir for the burner, a valve for the fuel supply, an air supply to the reservoir for forcing fuel supply to the 80 burner and having a line coacting to open the fuel supply valve simultaneously with the air forcing of the fuel supply to the burner, and a thermostatic control for the air supply. 85

3. A burner, a reservoir, a fuel supply from the reservoir for the burner, a valve for the fuel supply, an air supply to the reservoir for forcing fuel supply to the 90 burner and having a line coacting to open the fuel supply valve simultaneously with the air forcing of the fuel supply to the burner, and a motor for the air supply. 95

4. A burner, a reservoir, a fuel supply from the reservoir for the burner, a valve 95 for the fuel supply, an air supply to the reservoir for forcing fuel supply to the burner and having a line coacting to open the fuel supply valve simultaneously with the air forcing of the fuel supply to the 100 burner, a motor for the air supply, and a thermostatic control for the motor.

5. A burner, a reservoir, a fuel supply from the reservoir for the burner, a valve for the fuel supply, an air supply to the 105 reservoir for forcing fuel supply to the burner and having a line coacting to open the fuel supply valve simultaneously with the air forcing of the fuel supply to the burner, a furnace heated by the burner, and 110 a duct in the furnace for heating the air supply to the burner.

6. A burner, a reservoir, a fuel supply from the reservoir for the burner, a valve for the fuel supply, an air supply to the 115 reservoir for forcing fuel supply to the burner and having a line coacting to open the fuel supply valve simultaneously with the air forcing of the fuel supply to the burner, said air supply having a branch, 120 and a furnace for the burner into which furnace the branch extends on its way to the burner.

7. A cylindrical horizontal carbureter, a liquid fuel supply duct, an adjacent hot air 125 supply duct for vaporizing the entering fuel, and a burner outlet for the carbureter along its bottom precluding condensation accumulation in the carbureter.

8. A burner, a pressure air supply line to 130

the burner coacting to control burner operation, a supply for said line, a heater through which the line extends, a check valve in said line opened by normal air supply pressure, said valve disposed between the heater and supply, and means for adjusting said valve.

9. A heater installation including a fuel reservoir having a pressure air chamber, a burner, a pressure fuel line from the

reservoir to the burner, an air line extending to the burner and having a coil between the reservoir and burner heated by the burner, pneumatic control means for the fuel line to the burner, and additional control means 15 as an air fluctuation retarding device in the air line between the reservoir and burner.

In witness whereof I affix my signature.

STANLEY R. HARDWICK.
